(57) **CLAIM**

The ornamental design for a retainer for a hair clip, as shown and described.

DESCRIPTION

FIG. 1 is a perspective view of a retainer for a hair clip showing our new design;

FIG. 2 is a top plan view thereof;

FIG. 3 is a bottom plan view thereof;

FIG. 4 is a side view thereof;

FIG. 5 is a front view thereof; and,

FIG. 6 is a rear view thereof.

The broken lines showing three circular elements on the top and bottom surfaces of the retainer for a hair clip in FIGS. 1, 2 and 3 are for illustrative purposes only and do not form part of the claimed design.
